Primary Examiner—Caron D. Veynar

[57] CLAIM

The ornamental design for waffle iron plates, as shown and described.

DESCRIPTION

FIG. 1 is a top plan view;
FIG. 2 is a cross section taken along line 2—2 in FIG. 1;
FIG. 3 is a perspective view;
FIG. 4 is a bottom plan view; and,
FIG. 5 is a side elevation view, all other side views being identical.

The broken line showing of a waffle iron plate, hinge and handles in FIGS. 1 and 2 are for illustrative purposes only and form no part of the claimed design.
